ALUMINUM LIGHTWEIGHT BASKET

Kenneth S. Snow, Glassboro, N. J.

Application December 2, 1947, Serial No. 789,192

3 Claims. (Cl. 220—71)

1

This invention relates to baskets and more particularly to a basket that is fabricated from metal and is used for containing or shipping produce such as fruit, vegetables or similar perishable or non-perishable articles.

It is an object of the present invention to provide a basket of light weight material, such as aluminum, which will be strong, sturdy, well shaped, while still being of light weight.

Other objects of the present invention are to provide a basket which is of simple construction, easy to assemble, inexpensive to manufacture, and is free of sharp edges.

This basket will be used to replace the old type wooden slat baskets that are universally used for containing or shipping fruit and vegetables. This type of basket is waterproof, long lived and possesses salvage value that is not always present when wooden baskets are used. This basket can be produced by mass production, being light in weight, will save shipping costs and in the long run will be as inexpensive to the user as the old type of wooden baskets now used.

For other objects and for a better understanding of the invention, reference may be had to the following detailed description taken in connection with the accompanying drawing, in which:

Figure 1 is a top plan view of the basket;

Figure 2 is a cross-sectional view taken on line 2—2 of Figure 1;

Figure 3 is a fragmentary cross-sectional view of the bottom of the basket before the same has been pressed upwardly and inwardly.

Referring now to the figures, 10 represents staves which are ribbed at 11, and are arranged in circumferentially spaced fashion to provide spaces 12 therebetween for ventilation. This construction gives the stave the strength of much heavier material.

At the top of the basket is a wire ring 13 which is curled into the top of the staves 10 to give the basket crushing resistance. The size and circumference of the wire will depend upon the size of the basket made. This wire 13 may be made of steel or iron, but preferably of aluminum, in order to prevent rusting.

The staves 10 are of light weight aluminum, and the corrugations 11 run through substantially the entire length of the staves to within a short distance of the end of the stave, thereby leaving a flat metal section to be curled into the wire 13 at the top. There is a similar section at the bottom to be curled into the bottom plate

14 as its periphery 15 is curled upwardly to include the stave. The bottom 14 has corrugations 16 pressed therein in order to make the same rigid, as shown in Figure 3, and when the bottom has been finally pressed onto the staves, it will be concaved upwardly into the basket, as shown in Figure 2, to a greater extent than as shown in Figure 3.

A band 17 of aluminum extends about the 10 staves, and is fastened to each stave by a rivet 18, whereby to reinforce the basket against any tendency for the same to bulge upon great weight being rested upon the top of the basket. One 15 band is shown as being used, but it is understood that more can be used to further strengthen the basket, or in case a taller basket is wanted, taller staves and extra bands can be used, as desired.

Each stave has its side turned in, whereby to 20 provide a bent over head 19 along the stave, whereby to reinforce the same, and at the same time eliminate sharp edges.

The entire basket is preferably made of 25 aluminum, and is accordingly of light weight, free from rust, and has salvage value, when it becomes sufficiently destroyed, to be useless as a basket.

While various changes may be made in the 30 detailed construction, it shall be understood that such changes shall be within the spirit and scope of the present invention, as defined by the appended claims.

I claim:

1. A basket comprising a plurality of staves 35 formed of light weight metal and corrugated throughout substantially the entire length thereof and having flat top and bottom sections, a ring at the top of the basket and the top flat sections being rolled under the ring whereby to 40 form a rigid top of the basket, a bottom having a periphery rolled onto the bottom flat portions of the staves, said bottom being indented upwardly and inwardly and having reinforcing corrugations therein and an enlargement along the 45 vertical edges of said staves to reinforce said staves and eliminate the sharp edges of said staves.

2. A basket comprising a plurality of staves 50 formed of light weight metal and corrugated throughout substantially the entire length thereof and having flat top and bottom sections, a ring at the top of the basket and the top flat sections being rolled under the ring whereby to form a rigid top of the basket, a bottom having 55 a periphery rolled onto the bottom flat portions

of the staves, said bottom being indented upwardly and inwardly and having reinforcing corrugations therein and an enlargement along the vertical edges of said staves to reinforce said staves and eliminate the sharp edges of said staves, and a band extending about the staves and connected thereto whereby to prevent bulging of the basket.

3. A basket comprising a plurality of staves formed of light weight metal and corrugated throughout substantially the entire length thereof and having flat top and bottom sections, a ring at the top of the basket and the top flat sections being rolled under the ring whereby to form a rigid top of the basket, a bottom having a periphery rolled onto the bottom flat portions of the staves, said bottom being indented upwardly and inwardly and having reinforcing corrugations therein and an enlargement along the vertical edges of said staves to reinforce said staves and eliminate the sharp edges of said staves, said staves being circumferentially spaced from one another whereby to provide spaces be-

5

tween them for the ventilation of air through the basket, said staves having their side edges turned over to be reinforced and to eliminate the sharp edges thereof.
